UNITED STATES PATENT OFFICE.

RALPH REUBEN KOHN, OF PHILADELPHIA, PENNSYLVANIA.

DRAFT DEVICE FOR LOCOMOTIVES.

Application filed June 15, 1920. Serial No. 389,117.

To all whom it may concern:

Be it known that I, RALPH REUBEN KOHN, a citizen of the United States, residing at 1720 N. Creighton St., Philadelphia, in the 5 county of Philadelphia and State of Pennsylvania, have invented a certain new and useful Draft Device for Locomotives, of which the following is a specification.

My invention relates to the draft mechanism of locomotives by which the hot gases 10 from the furnaces are caused to flow through the tubes of the boiler.

The purpose of my invention is to induce or assist the draft by a blast of air 15 secured through the movement of the engine, and passed up through the petticoat pipe as in the case of the steam exhaust, and at the same time control the division of steam and air by a baffle acting as a valve.

20 A further purpose is to use the air draft and steam exhaust at will or together for the purpose of causing the blast through the petticoat pipe, permitting the use of the exhaust steam for water heating during a part 25 of the time, at least, while the engine is in motion.

Further purposes will appear in the specification and in the claims.

I have preferred to illustrate my invention by but one main form, selecting a form 30 which is practical, efficient and inexpensive, and which at the same time well illustrates the principles of my invention.

Fig. 1 is a side elevation of the preferred 35 form of my invention, the locomotive being dotted in place.

Fig. 2 is a fragmentary vertical central section, showing a blast pipe which may be used in Fig. 1.

40 Figure 2^a is a section showing a conventional form of 3-way valve.

In the drawings similar numerals indicate like parts.

The induction of draft through the fire 45 tubes of the locomotive boiler by exhaust steam through a blast pipe 5 and into a petticoat pipe 6 within the smoke box 7 has been a common practice for many years. The use of an alternative path for the exhaust 50 steam through pipes 8 and 8', coupling 9 and coil 10 to exhaust at 11 through the water storage space of the tender 12 is also old per se, but has been previously limited to use with special engines.

55 By my invention I provide a flared inlet air pipe 13, projecting at the front of the

engine and connected by pipe 14 with the interior of the blast pipe 5 in such manner that the air driven in by reason of the air resistance met with by the engine in its travel, will enter the blast pipe and pass up 60 through the blast pipe into the petticoat pipe, serving the same purpose and acting in the same manner as in the case of the exhaust steam previously used.

I prefer to form a flare of the inlet 13, 65 chiefly on one side as 14, so as to permit it to be located nearly in horizontal line with the blast pipe without interfering with the opening of the front of the smoke box.

Within the blast pipe, I place a 3-way 70 valve 15 showing conventionally in Figure 2^a, controlling the passage of the exhaust steam through pipe 16 in either of two directions, sending it through the nozzle 17 up through the draft pipe or through the 75 outlet 18 to pipe 8 for water heating purposes or dividing the flow between these two paths, when the valve is in an intermediate position. This 3-way valve is operated by a stem 19, lever 20 and rod 21 80 from a hand lever 22 within the engine cab.

Though the invention thus far described is desirable in itself, and permits complete hand control of the steam, I prefer to use it in combination with a vane or blade 23 85 above the nozzle 17 and pivoted upon a rod 24. This pivot point is preferably to the left of a direct line up through nozzle 17, so that a blast of steam from the nozzle 17 will turn the vane upwardly out of the way, 90 when there is not a strong blast through the pipe 14. The pressures on the two parts of the under face of the vane to the right and to the left of the pivot rod in Fig. 2 are, or may be nearly enough balanced so that 95 a blast through pipe 14 upon the right hand side of the upper face of the vane turns the blade to the position shown in Fig. 2, giving full play to the air blast even though some exhaust steam be used also. The vane 100 need not at any time close the blast pipe entirely. Movement in clockwise direction can be limited by any stop and the valve may be restrained to any desired extent 105 against movement in counter-clockwise direction so as to shield the air inlet opening from steam blast when the steam is being used. In the position shown the vane serves as a baffle to direct the air upwardly through the blast pipe when the air blast is on.

110 By my means, with passage of the en-

gine through the air at the usual high rates of speed, the air blast is effective to take the place of, or assist the exhaust steam in inducing draft through the locomotive 5 boiler tubes, leaving a larger percentage, or all of the exhaust steam available for use in heating the water within the locomotive tank. My invention does not interfere in any way with induction of draft by live 10 steam when the engine is stationary.

I recognize that a part or all of the value of my invention may be obtained by other constructions without departing from the spirit and scope of my claims, and desire to 15 include all such constructions herein.

Having thus described my invention, what I claim as new and desire to secure by Letters Patent is:—

1. In a locomotive draft mechanism, the 20 combination of a locomotive smoke pipe, a stack leading therefrom, a petticoat pipe connected with the stack, a blast pipe beneath the petticoat pipe, a vane pivoted in the blast pipe and adapted to receive the 25 blast upon its under side, means for diverting the blast from the blast pipe laterally without passing it through the petticoat pipe, and an air blast connection leading into the blast pipe from the front of the 30 engine and for which the vane forms a baffle to divert the air blast up the stack.

2. In a locomotive draft mechanism, the 35 combination of a locomotive smoke pipe, a stack leading therefrom, a petticoat pipe connected with the stack, a blast pipe beneath the petticoat pipe, means for diverting the blast laterally from the blast pipe, a vane pivoted in the blast pipe and adapted to receive the blast upon its under side and 40 an air blast connection leading into the blast pipe from the front of the engine and for which the vane forms a baffle to divert the air blast up the stack, the vane being balanced so as to turn according to the relative 45 pressures of the blast and of the air draft.

3. In a locomotive draft mechanism, the combination of a locomotive smoke box, a stack leading therefrom, a petticoat pipe connected with the stack, a blast pipe be-

neath the petticoat pipe, an exhaust steam 50 pipe having a nozzle discharging into the blast pipe, a valve and connections whereby the exhaust steam may be diverted therefrom, a pivoted vane in the blast pipe above the nozzle against which the nozzle discharges with greater pressure on the rear side of said pivot than on the forward side and an air blast connection leading into the blast pipe from the front of the engine and discharging against the upper rear surface 60 thereof to turn the vane in the opposite direction to that caused by the steam blast thereon.

4. In a locomotive draft mechanism, a locomotive smoke box, a stack leading therefrom, a petticoat pipe connected with the stack, a draft pipe beneath the petticoat pipe, air blast connections to the draft pipe, having an opening at the front of the engine, exhaust steam connections for the blast 65 pipe, a feed water heating coil, connections from the exhaust steam thereto, a valve directing the exhaust steam into the blast pipe or the heating coil, or dividing therebetween at will, control for the valve and a tilting 70 vane in said blast pipe, adapted to be turned in one direction by exhaust steam passage through the blast pipe to shield the air inlet from steam outlet, and to be turned in the opposite direction by air inlet to permit air 75 passage therethrough.

5. In a locomotive draft mechanism, a locomotive smoke-box, a stack leading therefrom, a petticoat pipe connected with the stack, a draft pipe beneath the petticoat 80 pipe, air blast connections to the draft pipe, having an opening at the front of the engine, exhaust steam connections for the blast pipe, a feed water heating coil, connections from the exhaust steam thereto, a valve directing the exhaust steam into the blast pipe or the heating coil, or dividing 85 therebetween at will and a tilting vane located in the blast pipe, adapted to direct air in the blast pipe and pivoted within the 90 path of the exhaust steam through the blast pipe.

RALPH REUBEN KOHN.
